(57) **CLAIM**

The ornamental design for wings for lap desks, as shown and described.

DESCRIPTION

FIG. 1 is a front, elevated, right-quartering perspective view of the new design for wings for lap desks;

FIG. 2 is a top plan view of the design shown in FIG. 1;

FIG. 3 is a bottom plan view of the design shown in FIG. 1;

FIG. 4 is a rear elevational view of the design shown in FIG. 1;

FIG. 5 is a front elevational view of the design shown in FIG. 1; and,

FIG. 6 is a right side elevational view of the design shown in FIG. 1, the left side elevational view being the mirror image of FIG. 6.
